XEROGRAPHIC TONER DISPENSER

Patrick T. Ferrari, Pittsford, Russell R. Roberts, Ontario, and Joseph B. Stone, Penfield, N.Y., assignors to Xerox Corporation, Rochester, N.Y., a corporation of New York

Filed Dec. 28, 1964, Ser. No. 421,256
5 Claims. (Cl. 222—225)

This invention relates to dispensing apparatus and more specifically, to toner dispensing apparatus for use in xerographic machines.

In the process of xerography, development of a latent electrostatic image is produced by bringing finely-divided powder or toner into contact with a photoconductive surface. The powder is held on the photoconductive surface by the electrostatic charge in a pattern corresponding to the latent image. Thereafter, the developed xerographic powder image may be transferred to a support surface such as paper and fused thereto by the application of heat or solvent vapors. In the development system of xerographic machines, the powder supply is depleted as images are developed and it is necessary, periodically, to add toner to the development system. Toner, which comprises finely-divided pigmented resin, presents unique and unusual problems of storage and handling.

One of the methods in common use for developing electrostatic latent images is described in Walkup Patent 2,681,551 and is known as "Cascade Development." In this method, the powder or toner is mixed with a granular carrier material to produce a two-component developer which is poured or cascaded over the photoconductive surface. The function of the carrier material is to improve the flow characteristics of the powder and to produce on the powder, by triboelectrification, the proper electrical charge so that the powder will be attracted by the electrostatic charge in image areas.

The amount of toner in the development system is depleted during the development process and must be periodically replenished. This toner is added by means of a toner dispenser. Due to the low melting point desirable for proper fusing, the toner is adversely affected by heat, pressure and humidity producing an agglomerating effect within the dispenser. During the development process, the carrier assists the toner in improving the flow characteristics thereof and preventing clogging. Since the dispenser does not have the help of the granular carrier material to assist in keeping the toner from agglomerating, it is desirable to have a dispenser which will operate in a positive manner to insure dispensing of controlled amounts of toner.

In conventional development systems the amount of toner present in the developer systems affects the quality of copy produced. If there is an excess of toner non-image areas will pick up toner producing undesirable background. If there is a deficiency of toner in the system, the image will not be fully developed and the copy will be weak and light.

The average amount of toner used per copy can be readily determined. For example, in average line copy, printed material covers approximately 5 percent of the area of a page. It is therefore possible knowing the number of copies made and the amount of toner normally used per copy to determine the amount of toner to be added after a given number of copies. In this manner, equilibrium can be maintained in the system by replenishing the amount of toner used in the developer. Thus, metering is practical and useful in either a system where the number of copies is counted and toner is manually added or an automatic system where the toner concentration is measured and the toner dispenser actuated accordingly.

In development apparatus such as that disclosed in co-

2

pending application of Kaupp et al., Serial No. 348,950, filed March 3, 1964, alternate developer pods are used for storing developer material. The type of toner used in each pod is the same. However, the quantity of developer beads in each pod differs for use in developing line or toner copy. In the operation of the developer, one pod is closed off while the other is in use. It is necessary that the toner dispenser used in such a developer housing be capable of dispensing toner to either developer pod.

In automatic xerographic machines of the type disclosed in the above cited application, Serial No. 348,950, the developer housing including the toner dispenser is inverted during development. It is therefore, necessary to have a toner dispenser that is sealed and is not affected by rotational movement of the developer system.

The primary object of this invention therefore is to improve xerographic toner dispensers for replenishing toner to developer systems.

A further object of this invention is to improve toner dispensers to dispense a measured or metered amount of toner.

A still further object of this invention is to completely enclose toner dispensers for use in a xerographic developer housing which are inverted during operation.

Another object of this invention is to improve toner dispensers so that the dispensing of toner can be effected by a positive action which meters the amount of toner dispensed.

Another object of this invention is to improve toner dispensers to permit toner to be added to either pod of a two pod developer system.

These and other objects of this invention are attained by a completely enclosed toner dispenser in which measured amounts of toner are separated from the main toner supply and deposited in the developer system by a positive acting ejector member to either of two locations in a developer housing.

For a better understanding of the invention as well as other objects and further features thereof, reference is had to the following detailed description of the invention to be read in connection with the accompanying drawings, wherein:

FIG. 1 is a perspective view partly in section of a xerographic toner dispenser constructed in accordance with the present invention;

FIG. 2 is a sectional view of a developer housing incorporating the toner dispenser shown in FIG. 1;

FIG. 3 is a front view of the toner dispenser and mounting taken along lines 3—3 of FIG. 2;

FIG. 4 is an enlarged front view of the resilient pad and the dispensing plate of the toner dispenser shown in FIG. 1;

FIG. 5 is a partial top view of the dispensing plate shown in FIG. 1; and,

FIG. 6 is a schematic representation of the developer housing showing the cascade positions.

For purposes of illustration the toner dispenser constituting the present invention is shown in a flat plate development system of the type used in xerographic machines such as that disclosed in the above cited co-pending application Serial No. 348,950. In that type of apparatus, the xerographic plate is clamped in a developer housing such as the one generally indicated at 10. The xerographic plate 20 is clamped to the housing by means of a plate clamp 21. The developer housing is supported on the shaft 12 by a bracket 14 and is rocked about the shaft 12 to the cascade positions shown in dotted lines in FIG. 6. The bracket 14 is attached to a pair of rods 16 which pass through and are secured to the developer housing.

A xerographic plate 20 is held in the developer hous-

ing 10 by means of a plate clamp 21. A resilient seal 24 extends around the opening into which the xerographic plate is fitted to prevent spillage of developer material.

The bottom of the developer housing is divided into two pods 26 and 28 by means of wall 30. Each pod has a bottom section 32 and 34 respectively hinged to the wall 30 and secured in place by means of clamps 35. The clamps 35 grasp the bottom sections 32 and 34 by means of curved hooklike appendages 36 and 37 which extend from the bottom sections. The developer material may be removed from the developer pod by disconnecting clamp 35 and permitting either bottom section 32 or 34 to pivot downward dropping the developer material out of the bottom of the developer pod. A shaft 40 is mounted on top of the dividing wall 30 and supports a cover flap 42 which may be pivoted by means of a lever (not shown). The cover flap 42 alternatively covers either of the developer pods 26 or 28.

One developer pod contains a greater quantity of developer for use in developing continuous tone images while the other developer pod contains a lesser quantity of developer for use in developing line copy. The cover flap 42 may then be pivoted from the position shown in FIGURE 2 when it is desired to develop tone images and is positioned in the dotted line position when it is desired to develop line copy. It is also possible to use an electrode plate (not shown) if desired when developing tone images.

A toner dispenser generally designated as 50 is attached to the developer housing by sliding the dispenser along the bracket 51 which is secured to the developer housing. The purpose of the toner dispenser is to replenish a measured amount of toner to either pod 26 or 28 of the developer housing as is deemed necessary. The toner dispenser is mounted above the developer pods so that replenishment of the toner is easily accomplished. A dispensing plate 53 is slidably mounted on bracket 54 and may be actuated in the direction shown by arrow 55 by means of lever 56. The lever 56 is attached to actuating shaft 57. Attached to the actuating shaft 57 are actuating levers 58 which fit into plate brackets 59. A spring 60 which keeps plate 53 securely against bracket 54 is mounted between the actuating shaft 57 and the plate bracket 59. The toner particles 52 shown in FIG. 4, are dispensed from the interior 65 of the toner dispenser by means of chambers 62 located in dispensing plate 53.

To dispense the toner to developer pod 26 positioned on the left hand side of the developer housing as shown in FIG. 2, the plate 53 is first moved to the right by lever 56 where the chambers 62 will fill with toner. When the plate is returned to the left resilient polyurethane pad 64 will positively force the toner out of the chambers 62 as shown in FIG. 4. To dispense toner to the alternate developer pod 28, the plate 53 is first moved to the left where the chambers 62 will fill with toner. The plate is then returned to the right where it will engage the polyurethane pads 64. Thus, the dispensing plate 53 can be positioned in any one of 3 positions—one to the left, one to the right, and one in the center of the toner dispenser. When the plate 53 is returned the spring 60 serves to force the plate 53 against resilient polyurethane pads 64 which press down on top of the plate 53. The polyurethane pads 64 are mounted on the side walls 66 of the toner dispenser. The toner dispenser 50 is mounted in the developer housing on developer bracket 51. The bracket 54 mounted below the toner dispenser is slidably mounted on developer bracket 51. The toner dispenser is stabilized by means of a stabilizing bracket 67 which is mounted on the side wall of the developer housing. The developer bracket 51 is rigidly attached to the stabilizing bracket 67.

Toner material may be easily added to the toner dispenser by removing side plate 70 from the developer

housing and sliding the toner dispenser bracket 54 along the developer bracket 51 and thereafter removing cover or top wall 72 from the toner dispenser. The amount of toner added to either of the developer pods 26 or 28 will be equal to the volume of the chambers 62 in plate 53. The number of orifices can be varied to dispense a different amount of toner.

It can readily be seen that with a toner dispenser of this type, no toner would be lost from the dispenser during the cascading process, that is, during the pivoting of the developer housing 10 about pivot shaft 12. It is also possible to dispense toner to either the developer pod for use in developing tone images or the developer pod for use in developing line copy.

While the invention has been described with reference to the structure disclosed herein, it is not confined to the details set forth, and this application is intended to cover such modifications or changes as may come within the purposes of the improvements or the scope of the following claims.

What is claimed is:

1. A toner dispenser including:
an enclosed container adapted to hold a quantity of toner material and having a bottom wall movable between a first and second position;
means to move said bottom wall between the first and second positions;
a series of openings in the bottom wall of sufficient size to hold the amount of toner material to be dispensed and positioned in the bottom wall so that they are open to the interior of the container when the bottom wall is in the first position thereby receiving toner from the container and are open to the outside of the container when the bottom wall is in the second position;
ejecting means adjacent the bottom wall to eject toner material from the series of openings when the bottom wall is in the second position;
said ejecting means comprising a homogeneous resilient member mounted adjacent to the container in pressing contact with the bottom wall;
the resilient member being flexible to a degree sufficient to permit the member to deform and extend into the series of openings when in contact therewith to thereby force toner material out of the opening.

2. A device for dispensing a measured amount of xerographic toner material including:

a housing suitable for holding toner material having top, end, and side walls;
said side walls having resilient pads mounted on the bottoms of a plate slidably mounted adjacent the bottom of said housing and having a series of chambers therein;
brackets attached to said plate;
an actuating shaft journaled in the end walls of said housing;
actuating levers mounted on said actuating shafts;
said levers communicating with said plate brackets whereby said actuating shaft will move said plate between a first and a second position by means of said levers wherein said chambers will be exposed to the interior of the housing defined by said top, end, and side walls when in said first position;
said chambers thereby filling with toner and whereby said chambers will engage said resilient pads when in said second position;
said resilient pads thereby ejecting from said chambers a measured amount of toner equal to the volume of the chambers.

3. A device for dispensing a measured amount of xerographic toner including:
a housing suitable for holding toner material having top, end, and side walls;
said side walls having resilient pads mounted thereon;
a plate slidably mounted adjacent the bottom of said housing and having a series of chambers therein;

means to move said plate between a first and a second position wherein said chambers are exposed to the interior of the housing when the plate is in the first position said chambers thereby filling with toner and whereby upon movement of said plate to the second position said chambers will engage one of said resilient pads;

5

said resilient pad in the degree wherein said pad deflects into said chambers thereby ejecting from said chambers a measured amount of toner material equal to the volume of said chambers.

10

4. A toner dispenser for dispensing toner material including:

a housing suitable for holding toner material including a slidable bottom wall;

15

said bottom wall having chambers therein;

resilient pads mounted juxtaposed to and engaging said bottom wall; and

20

means to move said bottom wall between a first and a second position wherein said chambers are exposed to the interior of the housing when the bottom wall is in the first position filling said chambers thereby with toner and whereby upon movement of said bottom wall to the second position and chambers engage at least one of said resilient pads, said pad resilient in the degree wherein said pad deflects into said orifices thereby ejecting from said chambers a measured amount of toner material equal to the volume of said chambers.

25

5. A toner dispenser comprising:

an enclosed container adapted to hold a quantity of toner material and having a bottom wall movable to first, second and third positions;

means to move said bottom wall to said first, second and third positions;

two series of openings in the bottom wall of sufficient size to hold the amount of toner material to be dispensed and positioned in the bottom wall so that they are open to the interior of the container when the bottom wall is in the first and third positions thereby receiving toner from the container and are open to the outside of the container when the bottom wall is in the second position, thereby allowing toner material to be dispensed from either series of openings; ejecting means adjacent the bottom wall to eject toner material from the series of openings when the bottom wall is in the first or third position;

said ejecting means comprising two resilient members mounted adjacent the container in pressing contact with the bottom wall;

the resilient member being flexible to a degree sufficient to permit the member to deform and extend into the series of openings when in contact therewith to thereby force toner material out of the opening.
